UNITED STATES PATENT OFFICE.

HARRY M. ROSE, OF PHILADELPHIA, PENNSYLVANIA.

DESIGN FOR A PHOTOGRAPH-MOUNT.

52,406.

Specification for Design.

Patented Sept. 10, 1918.

Application filed June 13, 1918. Serial No. 239,897. Term of patent 3½ years.

To all whom it may concern:

Be it known that I, HARRY M. ROSE, a citizen of the United States, residing in Philadelphia, county of Philadelphia, State of Pennsylvania, have invented a new, original, and ornamental Design for a Photograph-Mount, of which the following is a specification, reference being had to the accompanying drawings, which form part thereof.

The figure is a plan view of the mount, which is of rectangular shape, the design thereon comprising an exterior rectangular border spaced from the edges of the mount, an interior rectangular border spaced from the exterior border, an orifice of substantial

size located centrally, the points of a star radiating therefrom and overlapping the border, and within the border and above the central orifice, an eagle overlapping a starred circle and flanked by shields.

I claim—

The ornamental design for a photograph mount, as shown and described.

In testimony of which invention, I have hereunto set my hand, at Philadelphia, Pennsylvania, on this 27th day of May, A. D. 1918.

HARRY M. ROSE.
